PER

UNITED STATES PATENT OFFICE

ROBERT WHITE, OF MOTT HAVEN, AND DAVID MORITZ, OF NEW YORK, N. Y.

IMPROVEMENT IN PUMPS.

Specification forming part of Letters Patent No. 131,644, dated September 24, 1872.

To all whom it may concern:

Be it known that we, ROBERT WHITE, of Mott Haven, county of Westchester, State of New York, and DAVID MORITZ, of New York, county and State of New York, have invented a new and Improved Pump, of which the following is a specification:

In the accompanying drawing, Figure 1 represents a front elevation, partly in section, of our improved pump; Fig. 2 is a vertical transverse section of the same on the line *c c*, Fig. 1; Fig. 3 is a horizontal section of the same on the line *k k*, Fig. 1; Fig. 4 is a detail vertical section on the line *c k*, Fig. 1; Fig. 5 is a detail side view of the pump-barrel with the valve-chamber removed; and Fig. 6 an inner face view of the valve-chamber.

Similar letters of reference indicate corresponding parts.

This invention relates to a new arrangement of valve-chamber, frame, and piston-rod guide for a reciprocating pump, and more particularly to such mode of fastening the valve-chamber that it can be freely turned to convert the pump into a vertical or horizontal one as may be desired. The invention consists, first, in so arranging the ports in and to a cylindrical valve-chamber, that the same will operate equally well, when turned in either direction, on the face-plate of the pump-cylinder. This enables the same to connect at the bottom or at the side with the suction-pipe, and on the top or side with the discharge-pipe, and thus to convert the pump into one drawing and discharging water in vertical or horizontal direction, as may be desired. The invention consists, also, in fastening the pump-cylinder to its frame by means of the suction-pipe and a nut thereon; also, in the arrangement of concave guides for the cross-head on the piston-rod; and in swiveling the guide-frame to the end of the cylinder, so that the operating-handle or lever can be turned to either side or into any desired position.

A in the drawing is the pump-cylinder, containing a reciprocating piston or plunger, B, on a piston-rod, C, and closed at one end by a solid head, *a*, and at the other end by an annular head, *b*, and packing *d*. The suction-pipe *e* projects from the middle of the cylinder downward through the supporting-frame *D*, and has a screw-thread cut on it to receive a

nut, *f*, under said frame, as shown in Fig. 2. By means of this pipe *e* and nut *f* the cylinder is fastened to the frame, being further supported near its ends on projecting saddle-pieces *g g* of said frame. The frame is made of suitable shape, size, and material, with a plate, *h*, directly under the pump, and a ledge, *i*, all around said plate, forming a drip-catch, which will prevent the destruction of wooden supports, or of devices that would otherwise receive the drip. The suction-pipe *e* is within the cylinder, but beneath the bore of the same, turned aside transversely to lead into a valve-chamber, *E*, which is attached to one side of the cylinder. This valve-chamber is of cylindrical form, and is shown to be supported by a center-pin, *j*, that projects from the side of *A*, and is held in place by a nut, *l*, fitted upon the end of the pin *j*. The covering-plate *m* of the valve-chamber is circular, and is also held in place by the pin *j* and nut *l*. Directly where the chamber *E* is in contact with the cylinder *A* the side of the latter is made straight, and formed into a circular enlargement, as is clearly shown in Fig. 5. The central part of this enlargement is recessed or sunk and divided diametrically into two curved channels, *n* and *n'*, which communicate, respectively, with the ports *o* and *o'* at the ends of the pump. The suction-pipe *e* ends in a curved groove, *p*, formed in the face of the above-mentioned circular enlargement nearer the edge of the same, as is also shown in Fig. 5. The valve-chamber *E* contains two horizontal partitions, *r r*, which are connected in the middle by a bridge, *s*, thus forming four chambers, *t*, *t'*, *t''*, and *t'''*. The four valves *u u'* and *u'' u'''* are in pairs fitted upon the perforated partitions *r r*, one on either side of the bridge *s* on each partition. A slot, *v*, in the lower chamber *t* communicates with the groove *p* and suction-pipe. Apertures *w w* in the middle chambers *t'* and *t''* communicate with the channels *n n'* and ports *o o'*, while from the upper chamber *t'''* extends the discharge-pipe *F*, containing a check-valve, *x*. This check-valve is of importance, as it supports the column of water in the discharge-pipe whenever the valve-chamber is opened for inspection or repair, in which case only the water actually contained in the valve-chamber will be wasted.

When the valve-chamber is applied in the

position shown in Figs. 1 and 2 the pump will draw and discharge water vertically; but the valve-chamber can be turned to bring the discharge-pipe into a horizontal position or inclined, in which case the pump will draw water vertically and discharge it horizontally or obliquely, or the suction-pipe may be coupled directly to the valve-chamber at y to communicate with the chamber t , in which case both suction and discharge will be horizontal. These remarks apply when the frame D stands horizontally, as shown. When the same is placed vertically against the side of a wall, well-curb, or other place the relations of the other parts will change in a corresponding measure.

The operation of the valves need not here be described, since it is not new, nor is anything claimed in the construction or arrangement of the valves. The valve-chamber, instead of turning on the pin j , may be held in place by outside bolts at or near its periphery, and allowed to be turned on the pump, the same as hereinbefore described.

The piston-rod C has a cross-head, a^2 , formed on its outer end and working between parallel guides $b^2 b^2$, which are formed in a frame, G . This frame has an annular plate, d^2 , formed at one end embracing the packing gland or ring e^2 , and held by a nut, f^2 , but so that it can be turned freely whenever said nut is loosened. The contact edges of the cross-head a^2 are convex, and those of the guides $b^2 b^2$ concave transversely, the lateral displacement of the cross-head being entirely prevented. H is the operating handle or lever, pivoted at g^2 to the guide-frame G , and at h^2 to the cross-head.

The frame G being swiveled to the end of the cylinder, allows the handle to be brought to either side or used vertically as may be desired. When it is desired to shorten the lever it can be pivoted with its end to the frame, and at the middle to the cross-head, whereby it will also be changed from a lever of the first class to one of the second.

Having thus described our invention, we claim as new, and desire to secure by Letters Patent—

1. The valve-chamber E , so applied to the pump that it can be turned thereon to regulate the direction of the discharge, substantially as set forth.
2. The channels $n n'$ connecting with the ports $o o'$ and the groove p , connecting with the suction-pipe e when formed on the side of a pump, substantially as herein shown and described.
3. The valve-chamber E , containing the compartments t, t^1, t^2 , and t^3 , and provided with the slot v and apertures $w w$, substantially as herein shown and described.
4. The guide-frame G , carrying the handle H and the cross-head a^2 when swiveled to the end of the pump-cylinder, substantially as specified.
5. The concave guides $b^2 b^2$, when arranged in combination with the convex-edged cross-head a^2 , as specified.

ROBERT WHITE.
DAVID MORITZ.
